CLAIM

The ornamental design for a set of massager and massager case as shown and described.

DESCRIPTION

FIG. 1 is a perspective view of the massager case showing my new design, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the massager, shown separately for ease of illustration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; and, FIG. 17 is a perspective view of the set of massager and massager case, shown in use with the massager received in the massager case and in an open configuration. The broken lines in the drawings depict portions of the set of massager and massager case that form no part of the claimed design.
